Primary Examiner—Janice E Seeger*Assistant Examiner*—Mary Ann Calabrese(74) *Attorney, Agent, or Firm*—Morgan, Lewis & Bockius LLP(57) **CLAIM**

An ornamental design for a combined display and vehicle, as shown and described.

DESCRIPTION

FIG. 1 is a back perspective view of my new design;

FIG. 2 is a back view of FIG. 1; and,

FIG. 3 is a side view of FIG. 1.

The broken lines showing elements of the display on a vehicle in the above described figures are for illustrative purposes only and form no part of the claimed design.

It is understood that the front, top, bottom and one of the sides that are not shown are not part of the claimed design.
